(57) **CLAIM**

The ornamental design for earphones, as shown and described.

DESCRIPTION

FIG. 1 is a perspective view of earphones according to a first embodiment of my new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a left side view, thereof;

FIG. 7 is a right side view;

FIG. 8 is a perspective view of earphones according to a second embodiment of my new design;

FIG. 9 is a rear elevational view thereof;

FIG. 10 is a front elevational view thereof;

FIG. 11 is a top plan view thereof;

FIG. 12 is a bottom plan view thereof;

FIG. 13 is a left side view, thereof; and,

FIG. 14 is a right side view.

The broken lines shown in the drawings form no part of the claimed design.
